DISPOSABLE BULB SYRINGE FOR MEDICAL AND SURGICAL IRRIGATION

Daniel A. Cronin, Jr., Concord, Mass., assignor to The Macbick Company, Wilmington, Mass., a corporation of Massachusetts

Filed Feb. 18, 1966, Ser. No. 1,109

Term of patent 7 years

(Cl. D83—12)

FIG. 1 is a view in elevation of a disposable bulb syringe for medical and surgical irrigation showing my new design;

FIG. 2 is a view like FIG. 1 with the syringe rotated 90° about its longitudinal axis;

FIG. 3 is a bottom plan view thereof;

FIG. 4 is a top plan view thereof.

This application is a continuation-in-part of my copending application Serial No. D-83,912, which is a continuation of my copending application Serial No. D-79,827 and both now abandoned.

I claim:

The ornamental design for a disposable bulb syringe for medical and surgical irrigation or the like, substantially as shown and described.
